(57) **CLAIM**

The ornamental design for an applicator for artificial eyelashes, as shown and described.

DESCRIPTION

FIG. 1 is a perspective view of an applicator for artificial eyelashes showing the new design;

FIG. 2 is a first side view of the applicator for artificial eyelashes;

FIG. 3 is a bottom view of the applicator for artificial eyelashes; the top view is a mirror image and is not shown separately;

FIG. 4 is a front view of the applicator for artificial eyelashes; and

FIG. 5 is a back view of the applicator for artificial eyelashes; and,

FIG. 6 is a second side view of the applicator for artificial eyelashes.

The broken lines depict portions of the article that form no part of the claimed design.

1 Claim, 5 Drawing Sheets
